UNITED STATES PATENT OFFICE.

JOHN CARBONE, OF SYRACUSE, NEW YORK.

JOURNAL MOUNTING.

Application filed January 26, 1926. Serial No. 83,832.

This invention relates to a driving connection for oil pumps of the Hills-McCanna type commonly used in connection with hoisting engines or cranes as made by the 5 Browning Company of Cleveland, Ohio.

These hoisting engines are mounted in an upright position upon a suitable supporting frame with the cylinder at the top connected to an underlying crosshead guide in 10 which the crosshead is vertically movable and is connected to a crank shaft some distance below the lower end of said guide while the oil pump for the hoisting engine is supported at or near the upper end of 15 the engine cylinder and is operated by a continuous and somewhat slender pitman rod through the medium of an additional crank shaft which is located in approximately the horizontal plane of the crank 20 shaft of the engine so that the connecting rod between the second-named crank shaft and pump lever extends vertically practically the entire distance from the crank shaft of the engine to and above the top of the 25 cylinder.

In the practical operation of hoisting engines or cranes of this character it is found that after a relatively short period of use 30 the vibration of the connecting rod between the pump lever and its crank shaft causes undue crystallization and resultant breakage of the rod near its connection with the crank shaft or near its connection with the pump lever due primarily to the excessive 35 length of the rod.

The main object of the present invention is to reduce to a minimum this liability of 40 breakage of any part or parts of the connection between the pump lever and its crank shaft by interposing in the connection a lever of the first kind and connecting opposite ends of the lever to the crank shaft and to the pump lever respectively by short rods.

Another object is to support the pivot for 45 the lever upon one of the studs with which the frame of the engine is provided.

Other objects and uses relating to specific 50 parts of the device will be brought out in the following description.

In the drawings:—

Figure 1 is a side elevation of a portion 55 of an upright hoisting engine showing the oil pump and crank shaft and my improved connections between the crank shaft and pump lever.

Figure 2 is a transverse sectional view of

a part of the same device taken on line 2—2, Figure 1.

As illustrated, this device comprises a lever —1— of the first kind journaled midway between its ends upon a suitable bearing —2— which in turn is supported upon the shank of a screw —3—.

The threaded end of this screw is engaged in a threaded aperture in one end of a coupling member —4— having its other end provided with a threaded socket —5— engaging the protruding threaded end of a screw stud —6— with which the frame as —A— of the engine is already provided, the coupling —4— being tightly screwed upon the threaded end of the stud —6— and provided with a set screw —7— for tightening the coupling upon the inner end of the screw —3— to hold the latter against turning. 75

An oil pump —P— indicated more or less diagrammatically in Figure 1 is mounted upon the engine frame near the upper end of the cylinder, not shown, and is provided with an operating lever —8— having 80 a threaded outer end upon which is mounted a collar —9— capable of being adjusted to vary the throw of the pump part operated thereby.

The collar —9— is provided with trunnions upon which is journaled a forked yoke —11—, the latter being connected by a rod —12— to the underlying end of the lever —1— through the medium of a pivotal pin —13—. 85

The other end of the lever —1— is connected by a rod —14— to a coupling member —15— which is pivoted at —16— to an engine-driven revolving member —18— the pivot —16— being located some distance to 90 one side of the axis of the member —18— and together with said member constituting a crank for reciprocating the rod —14— vertically.

This reciprocation of the rod —14— imparts rocking movement to the lever —1—, said rocking movement being transmitted to the pump operating lever —8— through the medium of the rod —12— and yoke —11— which forms a part of the rod —12—. 100

The oil pump —P— may be of any well-known oscillating type capable of feeding a lubricant to the cylinder and other parts of the engine if desired.

The object in employing the coupling 110 member —4— is to permit the lever —1— to be mounted upon the stud as —6— with

which the engine is already equipped and at the same time to support the lever in approximately the vertical plane of the pump lever —8— and crank disk —18— so that 5 the entire driving connection between the crank shaft or disk —18— and pump will lie in substantially the same vertical plane.

Under this construction it is evident that the connecting rods —12— and —14— will 10 be relatively short as compared with the distance between the crank shaft or operating member —18— and pump lever —8— which greatly reduces the vibration of those rods and incidentally prolongs the life 15 thereof.

What I claim is:

1. In a journal mounting for a lever of the first kind, a sleeve internally threaded in both ends, one end of said sleeve being 20 adapted to engage an engine stud, a screw

adapted to be threaded into the opposite end of said sleeve, the shank of said screw being provided with a bearing member of less diameter than the head of the screw, a lever journaled on such bearing, and means for 25 locking said screw in said sleeve.

2. In a journal mounting for a lever of the first kind, a sleeve internally threaded in both ends, one end of said sleeve being adapted to engage an engine stud, a screw 30 adapted to be threaded into the opposite end of said sleeve, the shank of said screw being provided with a bearing member of less diameter than the head of the screw, a lever journaled on such bearing, means for locking 35 said screw in said sleeve, and means for oiling said bearing.

In witness whereof I have hereunto set my hand this 23d day of January, 1926.

JOHN CARBONE.
